INSECT ELECTROCUTOR

Donald E. Gilbert, Jonesboro, Ark., assignor to Gilbert Electronics, Inc., Jonesboro, Ark.

Filed May 20, 1971, Ser. No. 145,596

Term of patent 14 years

Int. Cl. D22—06

U.S. Cl. D22—19

FIG. 1 is a front elevation of my insect electrocutor;
FIG. 2 is an elevation of the left-hand end of FIG. 1,
the right-hand end elevation being opposite hand;

FIG. 3 is a rear elevation;

FIG. 4 is a bottom view;

FIG. 5 is a sectional view along line 5—5 in FIG. 1,
and

FIG. 5A is an enlarged detail sectional view of an
upper left-hand portion of FIG. 5.

I claim:

The ornamental design for an insect electrocutor, as
shown.
